UNITED STATES PATENT OFFICE.

EMANUEL SCHAEFER, OF JACKSONVILLE, FLORIDA.

COMB-CLEANER.

1,362,746.

Specification of Letters Patent. Patented Dec. 21, 1920.

Applicaiton filed May 13, 1920. Serial No. 381,021.

To all whom it may concern:

Be it known that I, EMANUEL SCHAEFER, a citizen of the United States, residing at Jacksonville, in the county of Duval and 5 State of Florida, have invented certain new and useful Improvements in Comb-Cleaners, of which the following is a specification.

The invention relates to a comb cleaner 10 and has for its primary object to provide a device of this character, wherein either fine or coarse combs can be readily and easily cleaned to remove all foreign matter from between the teeth thereof, thereby rendering 15 the comb thoroughly sanitary for continued use.

Another object of the invention is the provision of a comb cleaner of this character, wherein at one end of the same is a 20 spool holder, for the carriage of a spool having wound thereon cloth gauze, the latter being in strip form and can be unwound the desired extent so that the required length of gauze can be cut and positioned 25 upon the cleaner whereby the teeth of a comb can be forced through the gauze strip for the removal of foreign matter clinging to the teeth of the comb on extracting the teeth from the strip, the strip being also 30 adaptable for receiving liquid such as hair tonic or water, so that simultaneously with the cleaning of the teeth of the comb a quantity of the liquid or water will be carried thereby for the treatment of the hair 35 in the subsequent use of the comb.

A further object of the invention is the provision of a cleaner of this character, wherein the construction thereof adapts the same for use in barber shops, hotels, boats, 40 railway cars, hospitals and private homes, and will insure the thorough cleaning of a comb so as to render the same sanitary and free from dirt and other foreign matter.

A further object of the invention is the 45 provision of a cleaner of this character, which is extremely simple in construction, readily and easily handled, thoroughly reliable and efficient in its purpose and inexpensive to manufacture.

With these and other objects in view, the 50 invention consists in the features of construction, combination and arrangement of parts, as will be hereinafter fully described, illustrated in the accompanying drawings, 55 and pointed out in the claims hereunto appended.

In the accompanying drawings:

Figure 1 is a top plan view of a cleaner constructed in accordance with the invention, showing the cloth gauze, extending 60 over the top of the cleaner.

Fig. 2, is the side elevation of a comb partially pushed through the gauze and engaged with the cleaning wires of the 65 cleaner.

Fig. 3 is a fragmentary vertical longitudinal sectional view through the cleaner.

Fig. 4 is a vertical transverse sectional view on the line 4—4 of Fig. 3.

Similar reference characters indicate corresponding parts throughout the several views in the drawing.

Referring to the drawing in detail, the cleaner comprises upper and lower spaced 75 parallel substantially rectangular shaped frames 5 and 6 respectively, the same being connected together at opposite ends through the medium of connected webs or end walls 7, while carried by one of these webs is a handle 8, and beyond the other end wall is 80 a spool holder 9, the latter being for a purpose hereinafter fully described.

In the lower frame 6 are arranged closely disposed transverse cleaning wires 10, the same being fastened in their close relation 85 to each other to the side bars of the frame in any suitable manner, while arranged in the upper frame 5, are transversely disposed cleaning wires 11, which are arranged at a greater distance apart from each other than 90

the wires 10 so that the rows of wires 10 will be used for cleaning fine combs and the wires 11 will be used for cleaning coarse 95 combs, the wires 11 being fastened to the side bars of the frame 5 in any suitable manner. Mounted in the holder 9 is a rotatable spool 12 on which is wound cloth gauze 13, in strip form, which is adapted to serve as a cleaning cloth and this gauze 13 can be unwound from the spool 12 to 100

the desired extent and after the requisite length thereof has been had the same is cut and superimposed upon either of the frames 5 and 6, with the cleaning wires 10 and 11 therein so that by forcing the teeth of a 105 comb through the cloth the said teeth will be cleaned and the foreign matter will thus be left upon the cloth.

The comb 14, is positioned relative to either of the frames 5 and 6 so that the 110 teeth of the comb can be forced through one of the frames for example the frame 5 as

shown in Fig. 2 of the drawings, and the wires 11 in said frame will act upon the adjacent surfaces of the teeth to remove dirt and accumulated foreign matter therefrom.

- 5 When the cloth gauze 13 is positioned on the frame 5 it also will aid in cleaning the teeth of the comb 14 to dislodge all foreign matter, which will be taken up or collected by the gauze 13, and the strip thereof after 10 the use in cleaning the comb is thrown away. It is of course understood that the teeth of the comb 14 can be pushed through the gauze 13 to the full extent of the length of the teeth so that the latter will be completely cleaned and all of the foreign matter dislodged from between the same by the wires 10 or 11 in the respective frames 5 15 and 6 of the cleaner.

The size of the cleaner can be varied and

- 20 it can be constructed so that it may be carried in the pocket or in a suitcase or other traveling bag and when constructed for the carriage thereof in the pocket, the holder 9 and spool 12 will be eliminated.

- 25 It will also be apparent that by dampening the gauze 13 with water the hair can be rendered moist in the use of the comb as the moisture from the gauze will be taken up by the teeth when the comb is being cleaned, also the gauze 13 can be moistened with hair tonic at the option of the user of the cleaner.

In the use of the cleaner the comb will be properly and thoroughly cleaned and the

same rendered sanitary. It is preferable to 35 construct the frames 5 and 6 and webs 7 and holder 8 from aluminum although the same may be made from any other suitable material.

What is claimed is:

1. A cleaning device of the character described, comprising a pair of spaced parallel rigid open frames of elongated formation connected together at their ends, a series of closely arranged cleaning wires in 45 one of said frames and disposed transversely thereof, a series of spaced cleaning wires arranged in the other frame transversely thereof, the last-named series of wires being spaced a greater distance apart 50 than the first-named series of wires, and a holder carried by the connecting portion at one end of the frames.

2. A cleaning device of the character described, comprising a pair of spaced parallel open frames, end webs connecting said frames, series of cleaner wires arranged transversely in the respective frames, means on one end of the connecting webs to form a holder, a spool holder carried by one of 60 the frames and disposed at the end thereof, remote from the holder, a spool journaled in said holder and a cloth mesh strip normally wound upon said spool and adapted to be extended over one of the frames.

In testimony whereof, I affix my signature hereto.

EMANUEL SCHAEFER.
